(57) **CLAIM**

The ornamental design for a visored cap with telescoping crown, as shown and described.

DESCRIPTION

FIG. 1 is a front perspective view of a visored cap with telescoping crown, showing my new design in an unfastened, unexpanded configuration;

FIG. 2 is a front perspective view of the invention in a fully expanded, fastened configuration;

FIG. 3 is a right side elevation view of the invention, in a fastened, unexpanded configuration, the opposite, side elevation view being a mirror image thereof;

FIG. 4 is a right side elevation view thereof, showing the invention partially expanded, the opposite, side elevation view being a mirror image thereof;

FIG. 5 is a right side elevation view thereof, showing the invention fully expanded, the opposite, side elevation view being a mirror image thereof;

FIG. 6 is a front elevation view of FIG. 3;

FIG. 7 is a front elevation view of FIG. 4;

FIG. 8 is a front elevation of view FIG. 5;

FIG. 9 is a rear elevation view of FIG. 3;

FIG. 10 is a rear elevation view of FIG. 4;

FIG. 11 is a rear elevation view of FIG. 5; and,

FIG. 12 is a rear perspective view of the invention as shown in FIG. 1.

The crosshatched pattern, although shown intermittently, is meant to represent fabric and is understood to be distributed uniformly over the surfaces of the claimed design, the visor excepted.

The broken line showing the straps/ties is indicated for ease of illustration and forms no part of the claimed design.
